BOTTLE CLOSURE

John Henry Moir, Oakland, Calif.

Application April 2, 1935, Serial No. 14,339

1 Claim. (Cl. 215—51)

This invention relates to closures for bottles, or the like, and particularly to a closure having integral portions thereof foldable to provide a pouring spout by means of which all or portions of the contents of the bottle may be removed therefrom without the necessity of removing the closure from the bottle.

Among the objects of the invention are to provide a bottle closure having portions thereof foldable to provide a pouring spout; to provide, in conjunction with a bottle closure of the class described, means for rendering the closure proof against the entrance therethrough of bacteria into the bottle; to provide an improved closure, having a pouring spout, for milk bottles which may be as economically manufactured as most of the types of closures, without pouring spouts, in general use; and to provide a disk type of closure, provided with a pouring spout, which may be readily interchanged with the familiar type of disk closures, for milk bottles, in widespread use, without in any way altering the design of that portion of the bottle for receiving the closure.

25 Referring to the drawing:

Figure 1 is a top plan view of a disk-shaped closure for a milk bottle incorporating the invention.

Figure 2 is a side elevation of the closure of Figure 1.

Figure 3 is a vertical sectional view of the closure of Figure 1 showing the pouring spout extended.

Figure 4 is a bottom plan view of the closure of Figure 1.

Figure 5 is a perspective view of the closure as mounted on a milk bottle and with the pouring spout extended.

In detail, the invention comprises a laminated 40 circular disk 6, of a diameter permitting its insertion in the throat recess of a milk bottle 7. The disk 6 is composed of a main body section 8 made of suitable sheet material such as fiberboard, and having a central tab portion 9 partially separated from the main portion of the disk by means of an arcuate slit 10 and a pair 45 of straight divergent slits 11. The two slits 11 terminate at a score 12, the latter providing a hinge by means of which the tab may be bent outwardly from the disk as shown in Figure 3. A portion of the tab, adjacent its free end, is removed therefrom along the chordal line 13 so as to provide a recess 14 which permits the user to insert his finger nail therein to facilitate movement of the tab.

Mounted on the back of the section 8 is a circular sheet 15 of relatively stiff material such as parchment and this sheet is provided with a central portion 16 outlined by a circular slit 17, a pair of divergent scores 18 and a transverse slit 19. Each of the scores and slits mentioned above are disposed so that they lie in registry with the slit 10, the divergent slits 11 and the score 12 respectively of the section 8. Extending from the portion 16 are a pair of opposed wings 20 separated from the body of the sheet 15 by curved slits 21 which join the slit 17, at one end thereof, and at the other end join the transverse slit 19. The purpose of the slit 19 is to permit separation of the portion 16 from the remainder of the sheet 15, when the spout is drawn through the aperture, for the reason that, in the absence of the slit, the portion of the sheet 15 adjacent the hinge of the spout would, due to being bent about a larger radius than the material of the disk, be liable to rupture.

All of the portions of the sheet 15 are adhesively secured to the section 8 with the exception of the wings 20 which may be prevented from adhering thereto by the application, to the areas underlying the wings, of a coating 22 of paraffin.

It will thus be seen that when the tab portion 9 is moved forward the portion 16 will, due to its connection therewith, be carried through the aperture 23 created in the section 8 by the removal of the tab 9 therefrom. Simultaneously with the movement of the tab 9 the wings 20 will assume positions vertical to the plane of the portion 16, as shown in Figures 3 and 5. This is caused by the curved edges 24 of the wings bearing against the straight sides of the aperture 23 as they are drawn therethrough.

When the pouring spout is in the position indicated in Figure 5 the contents of the bottle may be poured therefrom through the aperture 23 and, when it is desired to re-seal the bottle, the spout may be moved back to its normal position flush with the surface of the section 8 whereupon the aperture 23 will be closed.

In order to seal the closure against the entrance 45 of bacteria or other contaminating matter into the bottle, it is proposed to provide a sealing sheet 25 of "cellophane" or other like material which may be adhesively attached to the top surface of the closure. It is preferable that the "cellophane" be attached by means of a tacky or non-hardening adhesive so that the sealing sheet may be removed and replaced, to re-seal the bottle, several times without the adhesive losing its gripping properties.

Having thus described the invention, it will be seen that an improved closure for bottles or the like has been provided which greatly facilitates the removal of the contents thereof, and at the same time provides means for thoroughly sealing the bottle against the entrance thereto of contaminating matter. In addition to these features the provision of a pouring spout, of the proportions indicated, enables the user to pour the contents from wide necked bottles in a concentrated stream with the result that the stream may be more readily controlled and losses due to spillage, in transferring the contents of the bottle to other containers, are greatly reduced.

15 What I claim is:

A bottle closure comprising a disk of relatively thick fibrous material having a slit therein defining an opening and a tab complementary to and disposed within said opening, said tab being inte-

grally hinged to said disk at a side of said opening for free movement into and out of said opening so as to open and close the latter, a parent sheet of relatively thin stiff material overlying one face of said disk, said parent sheet having 5 therein a continuous slit defining a central portion separable from the remainder of the sheet, said remainder of the sheet being adhesively attached to the disk and said central portion of the sheet comprising an area overlying and adhesively 10 joined to said tab and free wing-shaped areas extending from opposite edges of said tab and overlying surfaces of said disk at each side of the opening thereof, and one portion of the continuous slit defining the separable central portion 15 of said parent sheet being disposed immediately overlying the hinge of said tab.

JOHN HENRY MOIR.
